KARL BAUMANN, OF URMSTON, ENGLAND, ASSIGNOR, BY MESNE ASSIGNMENTS, TO
WESTINGHOUSE ELECTRIC AND MANUFACTURING COMPANY, A CORPORATION OF
PENNSYLVANIA.

VACUUM BREAKER.

Application filed May 10, 1921. Serial No. 463,299.

To all whom it may concern:

Be it known that I, KARL BAUMANN, a citizen of the Confederation of Switzerland, and a resident of Northwoodhouse, Barnfield, Urmston, in the county of Lancaster, England, have invented a new and useful Improvement in Vacuum Breakers, of which the following is a specification.

This invention relates to vacuum breakers 10 for steam condensers of the direct contact type.

Condensers of this type are usually provided with a water storage reservoir for preventing the level of the water in the condenser rising 15 to such a height as to enter the exhaust steam connections or even the prime mover itself before the vacuum breaker has had time to operate in the event of the speed of the extraction pump being reduced from any cause 20 without the quantity of the injection water being reduced proportionately at the same time.

Such water storage reservoir or capacity has heretofore been provided mainly by increasing the height of the main body of the 25 condenser and the present invention has for its object to provide an improved construction of condenser having the desired water storage capacity but in which the over-all height of the condenser is kept small.

This is accomplished according to the present invention by forming the water storage reservoir at the side of the condenser.

In carrying out the invention according to 35 one form, a weir or weirs is or are formed extending upwards inside the condenser body to within a short distance of the outlet opening of the mixing cone. A float chamber containing the float operated vacuum 40 breaker communicates with the space enclosed by the weir or weirs. The water storage reservoir is located at the side of the condenser and is separated from the interior thereof by the weir or weirs, the height of 45 which is determined by the maximum height to which water may be safely permitted to rise in the condenser. Said reservoir is of such capacity as will amply contain the maximum quantity of water which could 50 flow through the injection nozzles during the period which must elapse between the opening of the vacuum breaker and the reduction of the quantity of injection water consequent upon the loss of vacuum in the con-

denser due to the inflow of air through the 55 vacuum breaker valve.

Suitable means are provided for draining the reservoir and where the air pump is of the rotary type this may conveniently consist of a pipe connection leading from the 60 reservoir to the second stage of the pump.

To enable the invention to be clearly understood it will now be described with reference to the accompanying drawings, in 65 which:—

Figure 1 is a front elevation partly in section, of a condenser constructed in accordance with the invention, and Figure 2 is an end elevation thereof, also partly in section.

In the drawings, 1 is the condenser body 70 or shell, 2 the steam inlet, 3 the inlet for the condensing water which passes through nozzles, some of which are shown at 4, into the mixing chamber 5, which terminates in a cone 6. 7 are the extraction pumps arranged 75 at the foot of the condenser, as shown, and 8 is the air pump which communicates with the condenser space by means of the pipe 9. As illustrated these pumps are of the rotary type but other kinds may be employed as 80 desired.

The air pump 8 is illustrated as a two-stage pump having a rotary first stage 8' and a second stage 8'' of the ejector type. The vacuum breaker is indicated at 10 and is of 85 usual construction, the operating float thereof being indicated at 11 and the air pipe connecting the mixing chambers with the vacuum breaker valve is indicated at 12.

14 are the weirs which are arranged in 90 the body of the condenser and extend upwardly to within a short distance of the outlet opening of the mixing cone 6, as clearly shown in Figure 1 the said weirs enclosing a space 15. An opening 16 is provided in the wall of one of the weirs 14 and places the space 15 in communication with a float chamber 17 containing the float 11 of the vacuum breaker 10. The storage reservoir is indicated at 18 and is arranged at the 100 side of the condenser body or shell 1 and may either be formed integral with the said casting or may be a separate casting attached to the condenser in any suitable manner. Suitable means are provided for draining the 105 reservoir 18 and in the drawing 19 is a pipe connecting the reservoir with the second stage 8'' of the air pump 8 for this purpose.

The normal level of the water in the condenser, that is to say, in the space 15 is indicated at 20. Should, however, the water level rise, as would happen for example if the speed of the extraction pump were suddenly reduced from any cause without the supply of injection water being proportionately reduced, the water passing through the opening 16 into the float chamber 17 10 operates the vacuum breaker 10. Should the level continue to rise during the interval of time that elapses between the opening of the vacuum breaker valve and the reduction of the supply of injection water, the water 15 will flow over the weirs 14 into the storage reservoir 18 which is of such capacity as will amply contain the maximum quantity of water which could flow through the injection nozzles before the supply is reduced 20 consequent upon the loss of vacuum in the condenser due to the inflow of air through the vacuum breaker valve.

While I have shown my invention in but one form, it will be obvious to those skilled 25 in the art that it is not so limited, but is susceptible of various other changes and modifications, without departing from the spirit thereof, and I desire, therefore, that only such limitations shall be placed there- 30 upon as are imposed by the prior art or as are specifically set forth in the appended claims.

What I claim is:

1. In combination with a steam condenser 35 of the direct contact type, a storage reservoir and means for permitting water to flow from the body of the condenser into the storage reservoir when a permissible maximum high level of water within the condenser body has been reached 40
2. In combination with a steam condenser of the direct contact type, a storage reservoir, and a weir separating the body of the condenser from the storage reservoir, the 45 height of which corresponds to the maximum height to which it is desired water shall be able to rise in the condenser.
3. In combination with a steam condenser

of the direct contact type, a storage reservoir, means for permitting water to flow 50 from the body of the condenser into the storage reservoir when a permissible maximum high level of water within the condenser body has been reached, an air extraction pump, and a pipe connecting the 55 storage reservoir with an operative portion of said pump for the purpose of draining said reservoir.

4. In combination with a steam condenser of the direct contact type, a storage reservoir, a weir separating the body of the condenser from the storage reservoir, the height of which corresponds to the maximum height to which it is desired water shall be able to rise in the condenser, an air extraction 60 pump of the two stage type, and a pipe connecting the storage reservoir with the second stage of said pump for the purpose of draining said reservoir.

5. In combination with a steam condenser 70 of the direct contact type, a storage reservoir at one side of the condenser, a weir separating the body of the condenser from the storage reservoir, the height of which corresponds to the maximum height to 75 which it is desired water shall be able to rise in the condenser, a float chamber at another side of the condenser, a weir separating the body of the condenser from the float chamber and having an opening there- 80 in at a lower level than the weir separating the reservoir from the condenser, and a float controlled vacuum breaker responsive to the level of water in the float chamber, the arrangement being such that upon an abnormal rise of water within the condenser body 85 the float operated vacuum breaker will be first operated to establish an atmospheric pressure within the condenser, and upon a continued rise of water to the permissible 90 maximum high level, the excess will flow into said reservoir.

In testimony whereof, I have hereunto subscribed my name this fourteenth day of April, 1921.

KARL BAUMANN.
